ADJUSTABLE LETOFF FOR LOOMS

Walter H. Wakefield, Worcester, Mass., assignor
to Crompton & Knowles Loom Works, Worcester,
Mass., a corporation of Massachusetts

Application February 15, 1946, Serial No. 647,943

3 Claims. (Cl. 139—109)

1

This invention relates to improvements in let-offs for looms and it is the general object of the invention to provide a let-off usable with light or heavy weight warps.

A loom may at one time be used for weaving a light fabric the warp of which is under relatively low tension and may at another time be used to weave a much heavier fabric the warp of which is under high tension. In a form of let-off which has gone into general use there is employed an escapement mechanism controlled by a brake the position of which is determined preferably by the whip roll. When light and medium weight fabrics are woven with a let-off of this type the escapement mechanism oscillates slowly enough to permit gradual turning of the warp beam when the brake is released. When heavy warps are employed however the tension is so high that the escapement mechanism is likely to oscillate too rapidly, thereby permitting rotation of the warp beam and reduction of warp tension at such a rate as to produce defects in the fabric.

It is an important object of my present invention to provide means by which the brake is caused to dampen rapid vibration of the escapement mechanism. As shown hereinafter I accomplish this result by holding one end of the brake shoe against the escapement mechanism, more particularly a lever forming part of it when the whip roll operates to move the greater part of the brake shoe out of the contact with the escapement lever. In this way the brake shoe is utilized not only to lock the let-off against operation, but also to restrain too rapid an oscillation of the escapement mechanism when heavy fabrics are being woven.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of a let-off mechanism having my invention applied thereto, the weight lever being shown in cross section,

Fig. 2 is an enlarged vertical section on line 2—2 of Fig. 1,

Fig. 3 is a side elevation looking in the direction of arrow 3, Fig. 2, showing the brake shoe in non-locking but oscillation restraining position relatively to the escapement lever, and

Fig. 4 is a view similar to Fig. 3 but showing the shoe in locking relation with respect to the escapement lever.

2

Referring to Fig. 1, the loom frame 10 has extending rearwardly therefrom an upper support 11 on which a lever 12 is pivoted as at 13. The lever 12 extends upwardly and has rotatably mounted thereon the whip roll 14 over which extends the warp W wound on the warp beam B.

Lever 12 cooperates with a horizontally rockable lever 15 moving about a stationary vertical axis 16 and having an arm 17 normally exerting a rearward force on lever 12 tending to move the whip roll backwardly, or to the left as viewed in Fig. 1. Lever 15 is connected to a link or rod 18 connected to a lever 19 rocking in a vertical plane about a fixed axis 20 on support 11. Depending from lever 19 is a rod 21 which passes through the forward end of a brake lever 22 and has a collar 23 secured thereto below lever 22. A relatively strong compression spring 24 exerts a downward force on the right hand part of lever 22 and exerts an upward force on a sleeve 25 the position of which is adjusted by a nut 26 threaded on rod 21.

Lever 22 rocks about a stationary stud 27 secured to a lower support 28 fixed to the loom frame. A small gear 29 rotates on stud 27 and meshes with a larger gear 30 secured to the beam B. Fast with respect to the small gear 29 is a gear 31 meshing with a pinion 32 rotatable about a fixed stud 33 on support 28. Fast with respect to pinion 32 is a gear 35 which meshes with a pinion 36 secured to a small stub shaft 37 rotatable in support 28. Keyed to the shaft 37 is an escapement or star wheel 38 notched as indicated in Fig. 1 for cooperation with the upper and lower lugs 39 and 40 respectively of an escapement lever 41 pivoted as at 42 relatively to the support 28. The escapement lever has a flange 45 which provides on the under side thereof a friction surface 46 for engagement with a brake shoe 47 pivoted as at 48 to the rear part of brake lever 22.

When the whip roll is in rearward position, a condition corresponding to relatively low warp tension, rod 21 will be in a relatively low position due to weights not shown on an arm 49 of lever 19 shown in section in Fig. 1. The spring 24 therefore exerts downward force on the forward part of lever 22 and the shoe 47 is held up against the surface 46 to lock the escapement mechanism and prevent turning of the warp beam. As the whip roll moves forwardly during locked condition of the warp beam incident to consumption of the warp by the weaving operation rod 21 is raised and the collar 23 eventually rocks lever 22 in a counter-clockwise direction

as viewed in Fig. 1 to move the brake shoe downwardly away from the escapement lever. The latter is therefore free to oscillate under forces transmitted to its lugs by the escapement wheel 38, and the latter is caused to turn by the pressure of the warp W which is transmitted through the train of gears already described. The whip roll when moves rearwardly and the brake shoe again locks the letoff.

The matter thus far set forth is of common construction and may be as described in patent to Payne No. 2,184,059.

As already suggested, the letoff thus far described operates satisfactorily throughout a rather wide range of warp tensions resulting from the weaving of fabrics of different weights. When a heavy fabric is being woven, however, resulting in the exertion of a high tensional force tending to turn the beam B, it is found that when the brake is released the star wheel 38 exerts such a large force on the escapement lever that the latter oscillates very rapidly with the result that there is a quick drop in warp tension. If the whip roll is of considerable weight it may not respond instantaneously to this reduction in warp tension and a loose pick in the fabric will result.

In order to restrain or dampen the rate at which the escapement lever tends to oscillate under these conditions I provide means for causing part of the brake shoe to remain in engagement with the friction surface 46 when the lever 22 rocks in such a direction as would otherwise effect complete release of the escapement lever by the brake shoe.

The means for carrying my invention into effect is shown more particularly in Figs. 2 to 4, and comprises a screw stud 50 extending vertically through and adjustable in a rear extension 51 of lever 22. This screw is held in adjusted position with respect to the lever extension 51 by a lock nut 52. A coil spring 53 surrounds the upper end of stud 50 and rests on a slabbed nut-like part 54 of stud 50 adapted to receive a wrench. A stem 55 forming the upper part of the screw lies within the spring 53 to guide the latter, and the upper part of spring 53 enters a pocket 56 formed in the rear part of the shoe 41. The normal effect of spring 53 is to exert an upward force on the rear part of the brake shoe, tending to cause the latter to turn around its pivot 48, but this tendency of the spring depends upon the position of the adjusting screw, being relatively low when the screw is in downward position and being relatively high when the screw has been threaded upwardly through extension 51.

When a warp which exerts light tension is being woven the escapement lever will require very little if any dampening and under these conditions the spring 53 will be adjusted to exert a light upward force on the brake shoe, or if desired will exert no upward force. When a heavy warp is being woven, however, the screw 50 will be moved to a relatively high position with respect to the lever extension 51, thereby causing spring 53 to exert an increased upward force on shoe 41. When lever 22 is rocked in a counter-clockwise direction as viewed in Figs. 1 and 4 under these conditions the forward part of the shoe will move down away from brake surface 46 to occupy some such position as indicated in Fig. 3. The rear part of the brake shoe, however, will be held up against the escapement lever by spring 53 and prevent the latter from oscillating too rapidly. It is to be understood

that under these conditions the escapement lever 41 will move in a right and left hand direction with respect to the brake shoe, but the rear part of the latter will always be in position to restrain the escapement lever during some part at least of its oscillation.

From the foregoing it will be seen that I have provided simple means by which the tendency of the escapement lever to vibrate or oscillate can be varied to adapt the letoff to the weight of the warp being used. The brake shoe which forms a normal part of the type of letoff mechanism to which the invention applies is utilized for this purpose. The brake shoe will have the greater part of its brake surface out of contact with the escapement lever when the whip roll is in forward position, but some part of the brake shoe will always be held against the escapement lever by spring 53 to restrain undue oscillation of the escapement lever when the adjusting screw 50 is in relatively high position incident to the weaving of heavy warp. When changing from light to heavy warp or vice versa the force exerted by the spring 53 can be adjusted readily by an appropriate adjustment of the screw 50 and the latter can be permanently mounted on the letoff mechanism. The upper extension 55 of stud 50 will hold the spring 53 in position when the stud is in low position and the dampening action on lever 41 has been either reduced or removed entirely.

Having thus described my invention, it will be seen that changes and modifications may be made by those skilled in the art without departing from the spirit and scope of the invention and I do not wish to be limited to the details herein disclosed, but what I claim is:

1. In letoff mechanism for a loom having a warp beam tending to turn during loom operation and having an escapement lever operatively connected thereto which when free to oscillate enables the beam to turn but which when prevented from oscillating prevents turning of the beam, the rate of turning of the beam varying with the rate of oscillation of said lever, a brake lever movable from one position to another position during loom operation, a brake shoe pivoted intermediate the ends thereof on said brake lever and held thereby in braking position to prevent oscillation of the escapement lever when said brake lever is in said one position thereof, said brake lever when in the other position thereof moving said brake shoe bodily away from braking position relatively to said escapement lever, and means interposed between the brake lever and one end of said brake shoe effective to hold said end of the brake shoe against said escapement lever to dampen oscillation of the latter when said brake lever is in said other position thereof.

2. In letoff mechanism for a loom having a warp beam tending to turn during loom operation and operatively connected to an escapement lever which when free to oscillate permits turning of the beam but which when held against oscillation prevents turning of the beam, a brake for the escapement lever, a brake lever, means pivotally connecting the brake lever to the brake at a point on the latter intermediate the ends thereof, said brake lever when in one position holding said brake against the escapement lever to prevent oscillation thereof and said brake lever when in another position moving said brake in a direction away from braking position with respect to the oscil-

lating lever, thereby permitting the latter to oscillate, and means on the brake lever effective when the latter is in said other position thereof to hold one end of said brake against said escapement lever to dampen oscillation thereof.

3. In letoff mechanism for a loom having a warp beam tending to turn during loom operation and operatively connected to an escapement lever which when free to oscillate permits turning of the beam but which when held against oscillation prevents turning of the beam, a brake for the escapement lever, a brake lever, means pivotally connecting the brake lever to the brake at a point on the latter intermediate the ends thereof, said brake lever when in one position holding said brake against the escapement lever to prevent oscillation thereof and said brake lever when in another position moving said brake in a direction away from braking position with respect to the oscillating lever, thereby permitting the latter to oscillate, and means on the brake lever effective when the latter is in said other position thereof to hold one end of said brake against said escapement lever to dampen oscillation thereof, said last named means including an ad-

25

justable member on said brake lever movable to positions at different distances from said one end of said brake and a spring operatively interposed between said member and engaging said one end of said brake.
